[57] CLAIM

The ornamental design for a hand saw blade cover, as shown and described.

DESCRIPTION

FIG. 1 is a front view of a hand saw blade cover showing my new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a top view of the hand saw blade cover off the saw, opened and laid out flat;

FIG. 8 is a bottom view of the hand saw blade cover off the saw opened and laid out flat;

FIG. 9 is a front view of a second embodiment of my new design;

FIG. 10 is a back view thereof;

FIG. 11 is a top view thereof;

FIG. 12 is a bottom view thereof;

FIG. 13 is a left side view thereof;

FIG. 14 is a right side view thereof;

FIG. 15 is a top view of the second embodiment off the saw, opened and laid out flat; and,

FIG. 16 is a bottom view of the second embodiment off the saw, opened and laid out flat.

The broken showings of the saw are for illustrative purposes only and form no part of the claimed design.
